METHOD AND APPARATUS FOR HYDRAZINE DECOMPOSITION

Otto J. Plescia, New York, N.Y., Russell M. Mantell, Newark, N.J., and Frederick J. Martin, Staten Island, N.Y., assignors to The M. W. Kellogg Company, Jersey City, N.J., a corporation of Delaware

Application May 13, 1949, Serial No. 93,006.

20 Claims. (Cl. 60—35.4)

This invention relates to the decomposition of hydrazine. In one aspect, this invention relates to a method and apparatus for the decomposition of hydrazine as a gas generant. More specifically in this aspect, the invention relates to an improved method and apparatus for the catalytic decomposition of hydrazine as a gas generant.

The use of hydrazine as a gas generant for turbines, supersonic vehicles, guided missiles, rockets and the like, has been found highly preferably over that of hydrogen peroxide, which has heretofore been catalytically decomposed for such purposes. In this respect, the use of hydrazine as a gas generant is particularly attractive by reason of its significantly greater performance efficiency and its greater stability which eliminates storage and transportation difficulties normally encountered in the handling of hydrogen peroxide as a gas generant.

It is, therefore, an object of the present invention to provide for an improved method for the decomposition of hydrazine.

Another object of the invention is to provide for an improved method and apparatus for the decomposition of hydrazine.

A further object of the invention is to provide for an improved method and apparatus for the catalytic decomposition of hydrazine as a gas generant.

Further objects and advantages inherent in the invention will be apparent to those skilled in the art from the following more detailed disclosure.

In the drawing:

The accompanying drawing illustrates, partly in cross-section, elevational views of apparatus for carrying out catalytic decomposition of hydrazine as a gas generant, either in a single reaction chamber (Figure 1) or in two reaction chambers (Figure 2). These hydrazine gas generators of the drawing are capable of developing an average chamber pressure of approximately 275 pounds per square inch absolute or higher.

The principal elements of the single reaction chamber of Figure 1 in the drawing comprise a shell 10, a header or bonnet 12 having a nozzle 14 or other conventional means for introducing hydrazine into the reaction chamber, a first plurality of foraminous metal membranes 16, a second plurality of foraminous metal membranes 18, and an exhaust nozzle 20.

Shell 10 in Figure 1 is a conventional cylinder constructed of $\frac{3}{8}$ inch stainless steel, approximately $10\frac{1}{2}$ inches in length and having an inside diameter of approximately 3 inches. Header 12 is a cylindrical section, having a flat or elliptical end, through which nozzle 14 for introducing hydrazine is inserted. This header is constructed of $\frac{3}{8}$ inch stainless steel and is connected to channel section 22 by conventional means known to those skilled in the art, such as by welding, bolting, threading or clamping. Channel 22 comprises a flanged cylindrical shell constructed of $\frac{3}{8}$ inch stainless steel. The lower side of channel 22 is connected in a suitable manner to the upper portion of shell 10.

The membranes represented by numeral 16 comprise

2

a plurality of foraminous metal membranes positioned transversely across the upper portion of the reaction chamber and attached to the walls of shell 10 by conventional means, such as welding, bolting or clamping, with the uppermost membrane preferably positioned at a point approximately 1 inch from header 12. This first plurality of foraminous metal membranes preferably comprises a plurality of metal screens of copper, iron, brass, stainless steel, or other metal surface, which are superimposed on alternate layers of granular catalyst particles, represented by numeral 24, and which are positioned in the hollow spaces between the metal screens, these spaces being represented by numeral 26. The catalyst composition will be fully discussed hereinafter during the description of the operation of the apparatus. The depth or total thickness of the above-mentioned alternate layers of screens and catalyst will vary with the capacity requirements of the reaction chamber, although it is preferred that the granular catalyst particles be positioned within hollow spaces 26 between alternate layers of the metal screens to a thickness of approximately $\frac{1}{4}$ inch. At this point it will be noted that while the above-mentioned first plurality of foraminous metal membranes is represented in the preferred form of the apparatus, comprising the single reaction chamber of Figure 1, as a series of metal screens superimposed on alternate layers of granular catalyst particles, it is possible in another modification of the apparatus, if so desired, to have only a single metal screen or foraminous metal membrane positioned across the upper portion of the reaction chamber, with a single layer of catalyst bed positioned on the screen. However, the modification represented in Figure 1 in the drawing is preferred, by reason that in employing the arrangement as shown, possible fusion or sintering of the catalyst and clogging of the metal screen is avoided.

The membranes represented by numeral 18 in Figure 1 also comprise a plurality of foraminous metal membranes, similar in construction to membranes 16. Membranes 18 preferably comprise a plurality of superimposed metal screens positioned transversely across the outlet end of the reaction chamber, and preferably attached to the walls of shell 10 by any conventional means known to those skilled in the art. The depth of these screens may also be of any suitable thickness, depending upon the capacity requirements of the reaction chamber. While the depth of screens 18 may vary from the thickness of a single screen to such a thickness of screen layers that the uppermost screen layer is almost in contact with the lowest screen comprising membranes 16, it is preferred that membranes 18 have a depth of at least several inches, in order to obtain satisfactory hydrazine decomposition. The hydrazine decomposition takes place for the most part within the area confined by metal screens 18 as will be fully discussed hereinafter during the description of the operation of the apparatus. Membranes 16 and 18 may be of any suitable mesh and preferably a 20 to 100 mesh and .016 inch wire.

Nozzle 20, which may be an exhaust nozzle, venturi, or any other means for conducting gases from the reaction chamber, has an upper enlarged section of about 3 inches inside diameter and a lower restricted section of about $\frac{1}{4}$ inch inside diameter. This nozzle or other outlet means may be fastened to the outlet end of shell 10, by threading, welding, bolting or clamping, known to those skilled in the art, and may be made of any suitable metallic material such as stainless steel, copper, brass or iron.

Numerical 14 in Figure 1 indicates a nozzle or any conventional means for introducing hydrazine into the reaction chamber, and preferably may be an adjustable atomizer nozzle, threaded or welded into header 12 and

extending into the reaction chamber. This nozzle may be constructed of any suitable material such as stainless steel, copper, brass or iron.

A valved-conduit 28 is attached to nozzle 14 for the introduction of hydrazine into the reaction chamber, the rate of flow being controlled by valve 30 in conduit 28. Conventional pumping apparatus, represented by pump 32, is connected to conduit 28 for pumping a supply of hydrazine from a suitable storage supply vessel 34 which is attached to pump 32 through conduit 36. Storage vessel 34 and conduits 28 and 36 are constructed of any suitable material such as $\frac{3}{8}$ inch stainless steel, or iron, the aforementioned conduits having an inside diameter of approximately $\frac{1}{4}$ inch. Numeral 38 indicates a break in the drawing and thus the apparatus is not shown in its true length.

In another embodiment of the apparatus of the invention, the two-reaction chamber apparatus of Figure 2 in the drawing, comprises an initiator chamber and a main decomposition or reaction chamber. The principal elements of the initiator chamber comprise a shell 40, a header or bonnet 42 having a nozzle 44 or other conventional means for introducing hydrazine into the initiator chamber, a truncated conical screen 46, a foraminous metal membrane 48 and a conduit for exhaust gases 50. The principal elements of the main reaction chamber comprise a shell 52, a header or bonnet 54 having a nozzle 56 or other conventional means for introducing hydrazine into the main reaction chamber, a plurality of foraminous metal membranes 58 and an exhaust nozzle 60.

Shell 40, in the initiator chamber in Figure 2, is a conventional shell constructed of $\frac{3}{8}$ inch stainless steel, similar to shell 10 in Figure 1, and approximately 4 inches in length having an inside diameter of approximately $1\frac{1}{4}$ inches. Header 42 is a cylindrical section, which may be similar in construction to header 12 in Figure 1, and through which nozzle 44 for introducing hydrazine into the initiator chamber is inserted. This header is connected to shell 40 by conventional means known to those skilled in the art, such as by welding, threading, or clamping.

Membrane 46 is preferably a truncated conical metal screen positioned longitudinally within the initiator chamber. This screen is fastened at its base to the walls of shell 40 directly below header 42, by any suitable conventional means such as welding or bolting, so that a hollow space 62 is formed between the walls of shell 40 and the screen. Screen 46 is preferably a metal screen of copper, iron, brass, stainless steel or other metal surface. Numeral 64 indicates granular catalyst particles positioned in hollow space 62 between the walls of shell 40 and screen 46. Membrane 48 is also a foraminous metal membrane or screen similar in construction to screen 46. Membrane 48 is positioned transversely across the outlet end of the initiator chamber and is attached to the walls of shell 40 by any conventional fastening means. This membrane is preferably slightly raised from the outlet end of the initiator chamber for the purpose of allowing free flow of gases from the initiator chamber.

A third membrane or metal screen 66, similar in construction to screen 48, is positioned transversely across the inlet end of the initiator chamber between header 42 and the base of screen 46. This membrane is fastened to the inner walls of shell 40 by any suitable conventional means such as welding or bolting. The hydrazine decomposition takes place for the most part, in the initiator chamber, within the area confined by metal screens 46 and 48.

Conduit 50 is attached to channel 68, the latter comprising a flanged cylindrical shell constructed of $\frac{3}{8}$ inch stainless steel which is attached to the walls of shell 40. Conduit 50 is preferably centered in channel 68 for the efficient introduction of exhaust gases from the initiator chamber to the main reaction chamber. Con-

duit 50 is approximately $1\frac{1}{2}$ inches in length, and constructed of stainless steel having an inside diameter of approximately $\frac{3}{8}$ inch. It is preferable that this conduit be as short as possible in order to minimize cooling of the hot reactor gases which are transferred through this conduit to the main reaction chamber, as will be fully discussed hereinafter during the description of the operation of the apparatus. Numeral 44 indicates a nozzle or any conventional means for introducing hydrazine into the initiator chamber, preferably an adjustable atomizer nozzle similar to atomizer nozzle 14 in Figure 1, and is threaded or welded into header 42 and extends into the initiator chamber.

Shell 52 in the main reaction chamber in Figure 2, is a conventional cylinder similar to shell 10 in Figure 1, constructed of $\frac{3}{8}$ inch stainless steel, approximately $10\frac{1}{2}$ inches in length and having an inside diameter of approximately 3 inches. Header 54 is a cylindrical section, similar to header 12 in Figure 1, having a flat or elliptical end, through which nozzle 56 for introducing hydrazine is inserted. This header is constructed of $\frac{3}{8}$ inch stainless steel, similar to header 12 in Figure 1, and is connected to channel section 70 by conventional means known to those skilled in the art, such as by welding, bolting, threading or clamping. Channel 70 comprises a flanged cylindrical shell, similar to channel 22 in Figure 1, and is constructed of $\frac{3}{8}$ inch stainless steel. The lower side of channel 70 is connected in a suitable manner to the upper portion of shell 52. Nozzle 56 is preferably inserted at the mid point in header 54 and extends into the main reaction chamber.

Membranes 58 comprise a plurality of foraminous metal membranes or screens, similar in construction to membranes 48 or 66 in the initiator chamber or metal screens 18 in the single reaction chamber in Figure 1. Screens 58 are positioned transversely across the upper portion of the main decomposition chamber preferably at a point approximately 1 inch from the header 54. Screens 58 are supported within the main reaction chamber, or are attached to the walls of shell 52 by conventional means known to those skilled in the art such as by welding or bolting. The depth of screens 58 may be of any suitable thickness depending upon the capacity requirements of the reaction chamber, and while screens 58 may vary from the thickness of a single screen, it is preferred that they have a depth of at least several inches. Screens 58, 46, 48 and 66 may be of any suitable mesh and preferably a 20 to 100 mesh and of .016 inch wire. Nozzle 60, which may be an exhaust nozzle, venturi or other means for conducting gases from the main reaction chamber, is similar in construction to nozzle 20 in Figure 1. This nozzle or other outlet means is fastened to the outlet end of shell 52 by threading, welding, bolting or clamping, known to those skilled in the art, and may be made of any suitable metallic material such as stainless steel, copper, brass or iron. Numeral 72 indicates a break in the drawing and thus the apparatus is not shown in its true length. Within this main reaction zone, hydrazine decomposition takes place for the most part within the area confined by metal screens 58.

A valved-conduit 74 is attached to nozzle 44 for the introduction of hydrazine into the aforementioned initiator chamber, the rate of flow being controlled by valve 76 in conduit 74. Conventional pumping apparatus, represented by pump 78, is connected to conduit 74 for pumping a supply of hydrazine from a suitable storage vessel 80 which is attached to pump 78 through conduit 82. Another valved-conduit 84 is attached at one end to conduit 74 and is connected at the other to nozzle 56 for the purpose of introducing hydrazine into the main reaction chamber, the rate of flow being controlled by valve 86. Storage vessel 80 and conduits 82, 74 and 84 are constructed of any suitable material, similar to storage vessel 34 and conduits 36 and 28 in Figure 1, such as stainless steel or iron.

It has been indicated that a metal screen 66 is positioned transversely across the base of screen 46 in the initiator chamber. It should be noted, however, that while it is preferable to employ this screen in the initiator chamber, the function of the apparatus may nevertheless be carried out successfully without screen 66 being present. It has also been indicated that screen 46 is preferably a truncated conical screen. In this respect it should be noted that while a truncated conical screen is preferred in the modification of the apparatus illustrated in Figure 2, other forms of metal screens may also be successfully employed such as a cylindrical screen.

In this respect, it should be noted that while membranes 16 in Figure 1 have been described as comprising a plurality of metal screens superimposed on alternate layers of the aforementioned catalyst particles, it is also possible to employ a cylindrical foraminous metal membrane or screen, for this purpose, positioned longitudinally within the reaction chamber, but at a distance of approximately $\frac{5}{8}$ inch from the walls of the reaction chamber, with the catalyst particles positioned within the hollow space formed between shell 10 and the above-mentioned cylindrical metal screen. In another modification of the metal screens comprising membranes 16, in Figure 1 in the drawing, it is possible to have the aforementioned cylindrical metal screen positioned in an opening running through the center of metal screens 16, if so desired. It should also be noted that screens 18 in Figure 1 and 58 in Figure 2 may also comprise a series of screens of copper wool, coils of metal gauze, or porous sintered metal disks, if so desired.

Furthermore, although shells 10, 40 and 52 in Figures 1 and 2 have been described as cylindrical in shape, it will be noted that while such shape is preferred other shapes such as spherical may also be successfully employed if so desired. It will also be noted that various other alterations and modification of the various features of the apparatus and the dimensions thereof may be practiced by those skilled in the art without departing from the scope of the invention.

OPERATION

In the operation of the apparatus of the single reaction chamber modification in Figure 1 of the drawing for carrying out the catalytic decomposition of hydrazine as a gas generant, hydrazine is drawn from storage vessel 34 through conduit 36 by pump 32. Hydrazine thus withdrawn from vessel 34 is introduced through atomizer nozzle 14 into the reaction chamber via valved conduit 30. Hydrazine thus introduced into the reaction chamber is preferably in the form of a hydrazine-water mixture in the weight ratio of approximately 4:1, although anhydrous hydrazine, or hydrazine diluted with other suitable diluents, in varying proportions such as ammonia or compounds of hydrazine such as hydrazine hydrate, either as a gas or liquid may also be successfully utilized in accordance with the method of the operation. Hydrazine is injected into the reaction chamber at atmospheric temperature through adjustable nozzle 14, preferably in the form of a fine spray at an initial flow rate of approximately one gallon per hour, and is subsequently increased to a higher flow rate by proper manipulation of valve 30 in conduit 28, such as a flow rate of approximately 30 gallons per hour or higher, in accordance with the method of operation hereinafter described.

Hydrazine thus introduced as a spray into the reaction chamber, passes through screens 16 into hollow space 26 where it is contacted by catalyst 24 in a fixed-bed state. Catalyst 24 may be any catalyst which at atmospheric temperature is effective for initiating the decomposition reaction. Various catalysts may be employed for this purpose and preferably a catalyst prepared from cobalt, copper and an alkali metal, or a catalyst prepared from elementary cobalt, copper and an alkali metal, or a catalyst prepared from an oxygen-containing compound of each

of these metals, or combination of any one or two of these metals with oxygen-containing compounds of any one or two of the remaining metals, in proportions such that these components on the metal weight basis consist of approximately 30 to 80% cobalt, 10 to 45% copper and 10 to 45% of the alkali metal (as more fully described in a prior and copending application Serial No. 76,185, filed February 12, 1949, in which Russell M. Mantell and Otto J. Plescia of the present invention were the co-inventors in that application). Thus a preferred catalyst for initiating the reaction, may be a granular catalyst mass prepared by the ignition of a mixture of cobaltic oxide, cupric nitrate and sodium bicarbonate having a composition on a weight percent metal basis of approximately 57% cobalt, 21% copper and 22% sodium. The granular catalyst mass may be utilized in the form of pellets, extrusions, wires, beads and the like, which may have been previously activated by reduction with hydrogen or other suitable reducing media.

Upon contact with catalyst 24 in hollow spaces 26, initial decomposition of hydrazine introduced through screens 16 takes place. From the hot gases resulting from the aforementioned hydrazine decomposition in hollow spaces 26, heat is supplied by the passage of these gases to screens 18. During the passage of these gases through screens 18, the screens are heated to a temperature of at least about 400° F. or higher, depending upon the nature of the catalyst positioned in hollow spaces 26. In this respect, it will be noted that while hydrazine or hydrazine hydrate can be decomposed at a temperature within the range from about 572° F. to about 662° F., we have found that it is sufficient to preheat screens 18 to the aforementioned temperature of about 400° F. in order to carry out further self-sustained hydrazine decomposition, the screens thus acting as a catalyst. It has been indicated above that hydrazine is introduced into decomposition or reaction chamber at an initial flow rate of approximately one gallon per hour. This rate of flow is necessarily low in order to initiate the hydrazine decomposition reaction within hollow spaces 26 without flooding the catalyst with cool hydrazine liquid, thereby quenching the decomposition. However, this relatively low rate of hydrazine injection need only be maintained for such length of time as will permit screens 18 to reach the desired temperature of at least about 400° F., after which period the rate of hydrazine injection may be increased to a rate as high as 30 gallons per hour or higher, screens 18 having been sufficiently preheated, so that they now serve as the principal catalyst in decomposing further quantities of hydrazine at a sustained increased injection rate into the reaction chamber.

The hot decomposition products thus produced by decomposition of hydrazine by preheated screens 18 build up the pressure for the most part within the reaction chamber and pass through screens 18 and out through exhaust nozzle 20 at a temperature of between about 1300° F. and about 1500° F. It is possible to measure the pressure thus created, by the insertion of a pressure tap at any point along the length of shell 10 and extending into the reaction chamber, if so desired, but which is not shown in the drawing.

In the operation of the two-section chamber modification of the apparatus in Figure 2 of the drawing, for carrying out the catalytic decomposition of hydrazine as a gas generant, hydrazine is drawn from storage vessel 80 through conduit 82 by pump 78. Hydrazine thus withdrawn from vessel 80 is introduced through atomizer nozzle 44 into the first reaction chamber or initiator chamber via valved conduit 74. Hydrazine thus introduced into this decomposition zone is preferably in the form of a hydrazine-water mixture in the weight ratio of approximately 4:1, although anhydrous hydrazine, or hydrazine diluted with other suitable diluents in varying proportions such as ammonia, or compounds of

hydrazine such as hydrazine hydrate, either as a gas or liquid may also be successfully utilized in accordance with the method of the operation. Hydrazine is injected into this reaction zone at atmospheric temperature through nozzle 44, preferably in the form of a fine spray at a flow rate of approximately one gallon per hour. This rate of flow, however, is not critical inasmuch as the introduction of hydrazine into the initiator reaction zone is only for the purpose of starting up hydrazine decomposition in order to utilize the decomposition products for preheating the screen catalyst, represented by numeral 58 in the main reaction zone, as more fully hereinafter described. Hydrazine introduced as a spray into the initiator chamber passes through screens 66 and 46 into hollow space 62 where it is contacted by catalyst 64 in a fixed-bed state. Catalyst 64 may be any catalyst which at atmospheric temperature is effective for initiating the decomposition reaction. Various catalysts may, therefore, be employed for this purpose, with catalysts such as described in the modification of the apparatus illustrated in Figure 1 being preferred. Upon contact with catalyst 64 in hollow space 62 initial decomposition of hydrazine introduced through screens 66 and 46 takes place. The hot gases resulting from the aforementioned hydrazine decomposition in hollow space 62 next pass screen 48 into the main reaction chamber, via conduit 50. As a result of the passage of these hot gases through conduit 50 into the main reaction chamber, screens 58 are heated to a temperature of at least about 400° F. or higher, depending upon the nature of the catalyst positioned in hollow space 62 in the initiator chamber. When screens 58 have been heated to the aforementioned temperature of at least about 400° F., an increased rate of hydrazine is next introduced through adjustable atomizer nozzle 56 into the main reaction zone, and the hydrazine decomposition reaction then becomes self-sustained. Hydrazine thus utilized for this purpose in the main reaction zone is supplied through valved-conduit 84 which is attached at one end to nozzle 56 and is connected at the other end to conduit 74 for pumping a continuous supply of hydrazine from storage vessel 80. Once the reaction in the main reaction zone has become self-sustaining following a sufficient preheating of screens 58, shut-off valve 76 in conduit 74 may be entirely closed, thus cutting off the further generation of hot gases from the initiator chamber which were previously supplied to the main reaction zone through conduit 50. Thereupon, valve 86 in conduit 84 may be so adjusted as to increase the rate of flow of hydrazine into the main reaction chamber, to a rate such as about 30 gallons per hour or higher. It will be understood that in the starting-up decomposition reaction in the initiator zone, valve 86 remains closed until such time as screens 58 have been brought up to the proper temperature sufficient for carrying on further hydrazine decomposition on a self-sustaining basis. When screens 58 have been preheated by the hot decomposition gases from the initiator chamber, valve 76 in conduit 74 is then completely closed and the increased flow of hydrazine from vessel 80 through conduit 84 is effected by proper adjustment of valve 86.

The hot decomposition products thus produced by decomposition of hydrazine by preheated screens 58 in the main reaction chamber build up the pressure for the most part within this zone and pass out through exhaust nozzle 60 at a temperature of between about 1300° F. and about 1500° F. It is also possible if so desired to measure the pressure thus created in the main reaction zone by the insertion of one or more pressure taps at any point along the length of shell 52 and extending into the reaction zone, but which is not shown in the drawing.

The following examples are offered as a means for

7
8
a better understanding of the invention and should not be construed as unnecessarily limiting to the invention.

EXAMPLE I

5 This example illustrates the results obtained in carrying out catalytic decomposition of hydrazine employing the apparatus and method of the single reaction chamber embodied in Figure 1 in the drawing. The reaction chamber consisted of a cylindrical stainless steel pipe 10½ inches in length with an inside diameter of 3 inches. To one end of the chamber was attached a ¼ inch exhaust nozzle, and at the other end was attached a fuel injection spray nozzle with a flow-rating of approximately 30 gallons per hour. Near the outlet end of the chamber a pressure tap was also inserted. Thermocouples were inserted into the top, bottom and middle portions of the chamber. A series of circular brass screens having a total thickness of 6 inches, a 20 mesh and made of .016 inch wire was positioned transversely across the upper portion of the initiator chamber at a distance of 1 inch from the top of the shell, and served as screens 16 in Figure 1 in the drawing. A granular mass prepared by the ignition of a mixture of cobaltic oxide, cupric nitrate and sodium bicarbonate having a composition on a weight percent metal basis of approximately 57% cobalt, 21% copper and 22% sodium was pelleted and employed as catalyst 24 in hollow space 26 between alternate layers of brass screens 16. Another series of superimposed circular brass screens having a total thickness of ½ inch was positioned transversely across the outlet end of the reaction chamber, similar in construction to screens 16 and served as screens 18 in Figure 1 in the drawing. An aqueous solution containing approximately 80% hydrazine was fed into this reaction chamber through atomizer nozzle 14 and the resulting chamber temperatures and pressures were recorded from a series of runs as given in Table I below:

Table I

Fuel Flow, lb./sec.	Chamber Temperatures, ° F.			Chamber Pressure (p.s.i.a.)
	Top	Middle	Bottom	
0.0075	1,435	1,170	780	255
0.0085	1,485	1,265	973	335
0.0095	1,500	1,333	1,075	405
0.0095	1,455	1,405	1,240	445
0.01	1,455	1,405	1,180	445

EXAMPLE II

5 This example illustrates the results obtained in carrying out catalytic decomposition of hydrazine employing the apparatus and method of the two-reaction chamber embodiment in Figure 2 in the drawing. The initiator chamber, as in Figure 2 in the drawing, consisted of a cylindrical stainless steel pipe approximately 4 inches in length with an inside diameter of approximately 1¾ inches. Screen 46 in this initiator chamber was an 80 degree truncated conical brass screen employed as a retaining membrane together with brass screens 66 and 48 positioned across the inlet end and outlet ends, respectively. A granular catalyst having a composition similar to the catalyst employed in the method and apparatus in Example I was positioned in hollow space 62 between the walls of the initiator chamber and brass screen 46. Hydrazine at an initial flow rate of approximately one gallon per hour was introduced through nozzle 44 in the initiator chamber. The resulting hot decomposition products from the initiator chamber were permitted to pass into the main reaction chamber. The main reaction chamber consisted of a stainless steel pipe approximately 10½ inches in length and having an inside diameter of approximately 3 inches with a series of superimposed circular brass screens having a total thickness of 2 inches, and similar to brass screens 18 in the

reaction chamber of Figure 1 in the drawing, and serving as screens 58 in Figure 2 in the drawing, was positioned transversely across the upper portion of the main decomposition chamber at a point approximately 1 inch below the point of introduction of the hot decomposition gases from the initiator chamber. When screens 58 had been preheated to approximately 400° F. the flow of hydrazine into the initiator chamber was cut off and hydrazine was then introduced through nozzle 56 into the main reaction chamber. Thermocouples were inserted into the top, bottom and middle portions of the main reaction chamber, and a pressure tap was inserted near the end of this chamber. At the end of this reaction chamber was attached a $\frac{1}{8}$ inch exhaust nozzle. The resulting chamber temperatures and pressures in the main reaction chamber were recorded from a series of runs as given in Table II below:

Table II

Fuel Flow, lb./sec.	Chamber Temperatures, ° F.			Chamber Pressure (p.s.i.a.)
	Top	Middle	Bottom	
0.018	705	1,515	1,045	165
0.027	628	1,508	1,305	235
0.0029	550	1,435	1,358	270
0.037	510	1,475	1,350	295
0.038	485	1,515	1,350	315

Having thus described our invention, we claim:

1. A method for decomposing hydrazine which comprises: contacting hydrazine with a catalyst, which at a relatively low temperature is effective for initiating the decomposition reaction, whereby at least a portion of said hydrazine is decomposed with the liberation of heat; exposing a second catalyst, comprising a foraminous metal membrane composed of a material selected from the group consisting of brass, copper, iron and steel, to the heat of decomposition liberated by contact of hydrazine with said first catalyst to preheat said second catalyst to a temperature effective to promote the decomposition of hydrazine; and contacting the thus heated second catalyst with further quantities of hydrazine to effect decomposition thereof.

2. A method for decomposing hydrazine which comprises: contacting hydrazine with a catalyst, which at a relatively low temperature is effective for initiating the decomposition reaction, whereby at least a portion of said hydrazine is decomposed with the liberation of heat; passing the resulting heated decomposition products from contact with said first catalyst over a second catalyst, comprising a foraminous metal membrane composed of a metal selected from the group consisting of brass, copper, iron and steel, to preheat said second catalyst to a temperature effective to promote the decomposition of hydrazine; and contacting the thus heated second catalyst with further quantities of hydrazine to effect decomposition thereof.

3. The process of claim 2 wherein said first catalyst comprises an effective amount of each of cobalt, copper and an alkali metal.

4. The process of claim 2 wherein said first catalyst comprises an effective amount of each of a metallic cobalt and an oxide of each of copper and an alkali metal in proportions such that these components of the catalyst on the metal weight basis consist of approximately 30-80% cobalt, 10-45% copper and 10-45% alkali metal.

5. The process of claim 2 wherein said first catalyst comprises an effective amount of an oxide of each of cobalt, copper and an alkali metal in proportions such that these components of the catalyst on the metal weight basis consist of approximately 30-80% cobalt, 10-45% copper and 10-45% alkali metal.

6. The process of claim 2 wherein said second catalyst comprises a brass screen.

7. The process of claim 2 wherein said second catalyst comprises a copper screen.
  8. The process of claim 2 wherein said second catalyst comprises an iron screen.
  9. A method for decomposing hydrazine which comprises: contacting hydrazine in a first reaction zone with a catalyst, which at a relatively low temperature is effective for initiating the decomposition reaction, whereby at least a portion of said hydrazine is decomposed with the liberation of heat; exposing in a second reaction zone a second catalyst, comprising a foraminous metal membrane composed of a material selected from the group consisting of brass, copper, iron and steel, to the heat of decomposition liberated by contact of hydrazine with said first catalyst to preheat said second catalyst to a temperature effective to promote the decomposition of hydrazine; and contacting the thus heated second catalyst with further quantities of hydrazine to effect decomposition thereof.
  10. A method for decomposing hydrazine which comprises: contacting hydrazine in a first reaction zone with a catalyst, which at a relatively low temperature is effective for initiating the decomposition reaction, whereby at least a portion of said hydrazine is decomposed with the liberation of heat; passing the resulting heated decomposition products from contact with said first catalyst in said first reaction zone through a second reaction zone in contact with a second catalyst, comprising a foraminous metal membrane composed of a material selected from the group consisting of brass, copper, iron and steel, to preheat said second catalyst to a temperature effective to promote the decomposition of hydrazine; and contacting the thus heated second catalyst with further quantities of hydrazine to effect decomposition thereof.
  11. A method for decomposing hydrazine which comprises: contacting hydrazine in a first reaction zone with a catalyst, which at atmospheric temperature is effective for initiating the decomposition reaction, whereby at least a portion of said hydrazine is decomposed with the liberation of heat; passing the resulting heated decomposition products from contact with said first catalyst in said first reaction zone through a second reaction zone in contact with a second catalyst, comprising a foraminous metal membrane composed of a material selected from the group consisting of brass, copper, iron and steel, to preheat said second catalyst to a temperature of at least about 400° F. to promote the decomposition of hydrazine; and contacting the thus heated second catalyst with further quantities of hydrazine to effect decomposition thereof.
  12. A method for decomposing hydrazine which comprises: contacting hydrazine in a first reaction zone with a catalyst comprising an effective amount of cobaltic oxide, cupric nitrate, and sodium bicarbonate in proportions such that components of the catalyst on the metal weight basis consist of approximately 30-80% cobalt, 10-45% copper and 10-45% sodium bicarbonate, whereby at least a portion of said hydrazine is decomposed with the liberation of heat; passing the resulting heated decomposition products from contact with said first catalyst in said first reaction zone through a second reaction zone in contact with a second catalyst, comprising a foraminous metal membrane composed of material selected from the group consisting of brass, copper, iron and steel, to preheat said second catalyst to a temperature of at least about 400° F. to promote the decomposition of hydrazine; contacting the thus heated second catalyst with further quantities of hydrazine to effect decomposition thereof; and subsequently discontinuing the flow of hydrazine over said first catalyst, but continuing the flow of hydrazine over said second catalyst which is at a sufficiently high temperature to decompose hydrazine without preheating.
  13. The process of claim 2 wherein said first catalyst comprises an effective amount of cobaltic oxide, cupric

nitrate and sodium bicarbonate in proportions such that these components of the catalyst on the metal weight basis consist of approximately 30-80% cobalt, 10-45% copper and 10-45% sodium.

14. The process of claim 2 wherein said first catalyst comprises an effective amount of cobaltic oxide, cupric nitrate and sodium bicarbonate in proportions such that these components of the catalyst on the metal weight basis consist of approximately 57% cobalt, 21% copper and 22% sodium.

15. Apparatus for the decomposition of hydrazine, which comprises in combination: an elongated cylindrical first reaction chamber; a cylindrical metal screen positioned longitudinally within said first reaction chamber, forming a hollow space between the walls of said first reaction chamber and said metal screen, adapted to contain a granular catalyst disposed in said hollow space; means for introducing hydrazine into one end of said first reaction chamber within the enclosure formed by said metal screen; a second metal screen positioned transversely, across one end of said first reaction chamber; an elongated cylindrical second reaction chamber; a third metal screen positioned transversely across said second reaction chamber; a conduit communicating with one end of said first reaction chamber and one end of said second reaction chamber; means for introducing hydrazine into said second reaction chamber; and means for withdrawing products of reaction from said second reaction chamber.

16. Apparatus for the decomposition of hydrazine, which comprises in combination: an elongated cylindrical first reaction chamber; a truncated conical metal screen positioned longitudinally, within said first reaction chamber, forming a hollow space between the walls of said first reaction chamber and said metal screen, adapted to contain a granular catalyst disposed in said hollow space; means for introducing hydrazine into one end of said first reaction chamber within the enclosure formed by said metal screen; a second metal screen positioned transversely, across one end of said first reaction chamber; an elongated cylindrical second reaction chamber; a third metal screen positioned transversely across said second reaction chamber; a conduit communicating with one end of said first reaction chamber and one end of said second reaction chamber; means for introducing hydrazine into said second reaction chamber; and means for withdrawing products of reaction from said second reaction chamber.

17. Apparatus for the decomposition of hydrazine, which comprises in combination: an elongated cylindrical first reaction chamber; a truncated conical metal screen positioned longitudinally within said first reaction chamber, forming a hollow space between the walls of said first reaction chamber and said metal screen, adapted to contain a granular catalyst disposed in said hollow space; a nozzle for spraying hydrazine into one end of said first reaction chamber within the enclosure formed by said truncated conical metal screen; a second metal screen positioned transversely, across one end of said first reaction chamber; an elongated cylindrical second reaction chamber; a third metal screen positioned transversely across said second reaction chamber; a conduit communicating with one end of said first reaction chamber and one end of said second reaction chamber; a nozzle for spraying hydrazine into said second reaction chamber; and means for withdrawing products of reaction from said second reaction chamber.

18. Apparatus for the decomposition of hydrazine,

which comprises in combination: an elongated cylindrical first reaction chamber; a first metal screen positioned transversely across one end of said first reaction chamber; a truncated conical second metal screen positioned longitudinally within said first reaction chamber forming a hollow space between the walls of said first reaction chamber and said second metal screen, adapted to contain a granular catalyst disposed in said hollow space; a nozzle for introducing hydrazine into one end of said first reaction chamber within the enclosure formed by said truncated conical metal screen; a third metal screen positioned transversely across the other end of said first reaction chamber; an elongated cylindrical second reaction chamber; a fourth metal screen positioned transversely across said second reaction chamber; a conduit communicating with one end of said first reaction chamber and one end of said second reaction chamber; a nozzle for spraying hydrazine into said second reaction chamber; and means for withdrawing products of reaction from said second reaction chamber.

19. A method for decomposing hydrazine which comprises: contacting hydrazine with a catalyst, which at a relatively low temperature is effective for initiating the decomposition reaction, whereby at least a portion of said hydrazine is decomposed with the liberation of heat; exposing a second catalyst, comprising a foraminous metal membrane composed of a material selected from the group consisting of brass, copper, iron and steel, to the heat of decomposition liberated by contact of hydrazine with said first catalyst to preheat said second catalyst to a temperature of at least about 400° F. to promote the decomposition of hydrazine; and contacting the thus heated second catalyst with further quantities of hydrazine to effect decomposition thereof.

20. A method for decomposing hydrazine which comprises: contacting hydrazine with a catalyst, which at a relatively low temperature is effective for initiating the decomposition reaction, whereby at least a portion of said hydrazine is decomposed with the liberation of heat; passing the resulting heated decomposition products from contact with said first catalyst over a second catalyst, comprising a foraminous metal membrane composed of a material selected from the group consisting of brass, copper, iron and steel, to preheat said second catalyst to a temperature of at least about 400° F. to promote the decomposition of hydrazine; and contacting the thus heated second catalyst with further quantities of hydrazine to effect decomposition thereof.
